ATTORNEY

UNITED STATES PATENT OFFICE.

WILLIAM JOHN GOODWIN, OF EAST NORTHPORT, NEW YORK.

TRACK CONSTRUCTION.

Application filed January 30, 1922. Serial No. 532,771.

To all whom it may concern:

Be it known that I, WILLIAM JOHN GOODWIN, a citizen of the United States, residing at East Northport, in the county of Suffolk 5 and State of New York, have invented new and useful Improvements in Track Construction, of which the following is a specification.

This invention relates to improvements in railroad track construction and has for an 10 object the provision of a track wherein the rail sections are connected without the use of fish plates or bolts and in a manner to securely hold them in place, the construction 15 being such as to permit of expansion and contraction without injury to the track.

Another object of the invention is the provision of a track wherein the objectionable noise due to pounding at the rail joints 20 is eliminated, the wheels of the cars passing from one rail section to the other in a smooth and even manner and without liability of the wheels catching in or between the joints.

Another object of the invention is the provision 25 of a track of the above character, having means for preventing longitudinal creeping and possible disalignment of the rails.

Another object of the invention is the provision 30 of a railroad track which is simple and durable of construction and which is formed of rail sections of a novel character and which in addition, may be installed and maintained at a low cost.

With the above and other objects in view, the invention further includes the following 35 novel features and details of construction, to be hereinafter more fully described, illustrated in the accompanying drawings and pointed out in the appended claim.

In the drawings:—

Figure 1 is a plan view of a portion of a railroad track constructed in accordance 40 with the invention.

Figure 2 is an enlarged top plan view of the meeting ends of two rail sections, the 45 said ends being shown in separated relation.

Figures 3 and 4 are side views of the rail ends shown in Figure 2.

Figure 5 is an enlarged sectional view on the line 5—5 of Figure 1.

Referring in detail to the drawings, wherein like characters of reference denote corresponding parts, the reference character 50 10 indicates generally a railroad track which

is made up of rail sections 11 mounted on cross ties 12.

The rail sections 11 are of novel construction, being cross sectionally shaped intermediate their ends to provide a base 13, a head 14 and a connecting web 15 of substantially the same shape as the type of rails now in use. Each end of the rail sections however is of a different construction. Beginning at a point spaced inwardly from the end of the rail, the latter has each of its ends beveled, the bevel of one end being substantially parallel with the bevel at the opposite end. Also, beginning at a point adjacent the inner end of each beveled portions of the rail, the web 15 is thickened as shown at 16, so as to be of substantially the same width as the width of the head 14.

The rail at one of its beveled ends 17 has its web and head cut away so as to provide a supporting flange 18. The opposite end of the rail is undercut as shown at 19 so as to provide a shoulder and this shoulder is adapted to rest upon the supporting flange 18 when the adjacent ends of the rail sections are in track formation. By this means a support is provided for the ends of the rail sections and as the wheels of a car will engage the end of one rail section before leaving the other rail section, objectionable 85 pounding of the car wheels in passing over the rail joints is eliminated. It is preferred to arrange the rail sections as illustrated in Figure 1, that is, with the beveled ends of the joints of the rail sections upon one side 90 of the track extending in the same direction as those upon the opposite side in a reverse direction with all bevels extending inwardly in the direction of travel of the car as indicated by the arrow in Fig. 1. This will 95 prevent any tendency of the wheel flanges abutting the ends of the rails, with the result of possible accident.

Extending from the bottom of each rail section is a lug 20, which is adapted to engage a tie so as to prevent longitudinal 100 creeping of the rail sections. The rail sections may be secured to the ties by spikes 21 of the usual or any preferred type and as these spikes are arranged upon opposite 105 sides of the overlapping ends of the rails, the use of the usual fish plates and bolts may be dispensed with. At the same time, sufficient movement is permitted to allow for contraction or expansion of the rail sections. 110

The invention is susceptible of various changes in its form, proportions and minor details of construction and the right is herein reserved to make such changes as properly fall within the scope of the appended claim.

Having described the invention what is claimed is:—

In a car rail, a base, a head, a relatively narrow web connecting the base and head, said web increasing in width to the width

of the rail head from points spaced from each end of the rail, oppositely extending transversely beveled ends of the rail, a shoulder formed at one end of the rail by extending the base, and an undercut shoulder provided at the opposite end of the rail by extending the end of the rail head beyond the end of the base.

In testimony whereof I affix my signature. 20

WILLIAM JOHN GOODWIN.
